ELECTRICAL CONDUCTOR

Application filed November 14, 1927, Serial No. 232,988, and in Germany March 30, 1927.

This invention relates to electrical conductors, and particularly to multiplex cable circuits such as may be employed in telephony.

5 In a cable quad having two pairs of wires which may be used in phantom circuit arrangement, the relative positions of the four wires is of importance. Their position 10 largely determines the capacities of the side circuits of the phantom circuit as well as the disturbing capacitative coupling between the side circuits and the phantom. As regards the capacitative relationships, it is very important to guard against too great a capacity 15 in the phantom circuit. A low phantom capacity may be realized by twisting the two separately twisted pairs of conductors, one about the other, as is done in multiple twin cabling. Such a twisted quad has a very 20 irregular shape and it is difficult to construct such a quad to meet the requirements of precision in manufacture which are necessary to insure its freedom from high capacitative coupling. Far greater regularity in 25 construction may be obtained in a quad of square cross-sectional area in which the conductors located at adjacent corners of the square, or the conductors located at diagonally opposite 30 corners, are employed as one side circuit, the other remaining two conductors in either case being employed as the other side circuit. By pairing diagonally opposite conductors of a quad, it is possible to operate both the side circuits and the phantom circuit without substantial 35 interference. Yet, any undesirably high phantom circuit capacity of the latter arrangement may be greatly reduced and possibly completely avoided if adjacent conductors of the cable quad are paired to represent each of the side circuits. In the latter case, it will be clear that both side circuits run constantly parallel with each other and are coupled with one another.

40 To neutralize the coupling in side circuits which run constantly parallel to each other, transpositions may be employed as in open wire construction in which one or both side circuits may be transposed in accordance with definite rules in order that the couplings 45 of individual sections may be mutual. If

such transpositions be employed in the conductors of a cable quad in which the wires of each pair run parallel to the wires of the other pair, then the problem of interference elimination becomes more complex due particularly to the closer proximity of the side circuits resulting in greater interaction therebetween. Thus, it becomes apparent that special transposition schemes will be required for cable circuits which will differ considerably from those of open wire lines.

55 Any practical transposition scheme must provide as much freedom from coupling in its ideal construction as is provided by the well-known form of star quadded coupling, i. e., a quad in which the conductors are spirally wound about a common axis, the diagonally opposite conductors forming the respective side circuits. There is a greater 60 necessity for care in the case of cable circuits than in open wire lines to reduce the detrimental effects of unavoidable manufacturing irregularities to reduce any couplings which may arise through irregular or even systematic deviations of the wiring from their theoretical 65 positions. Any manufacturing irregularities may, in practice, introduce couplings only to a permissible and predetermined extent. A transposition has a 70 finite extension and has a definite influence on the coupling relationships as well as on the mutual capacities. Any useful transposition scheme must take into account any 75 unavoidable imperfections in the actual construction of a cable quad.

80 The primary advantage of this invention is to provide a transposition scheme which guarantees substantial freedom from coupling in the practical construction of the cable quad as well as in its ideal construction.

85 This invention may be better understood from the detailed description hereinafter following, when read in connection with the accompanying drawing, in which Figure 1 represents two side circuits of a quad having an equal number of transpositions; Figure 2 shows a similar arrangement of side circuits in which one has four transposition sections as compared to the one transposition section 90 in the other; Figure 3 shows a similar ar- 95

angement in which one side circuit has eight transposition sections as against three in the other; Figure 4 shows still another arrangement in which one side circuit has three transposition sections against a single transposition section in the other; Figure 5 shows a further arrangement in which one side circuit has eleven transposition sections and the other seven; and Figure 6 shows a modification of the arrangement in Figure 5 in which 10 the transposition sections in one side circuit are displaced with respect to those in the other.

A transposition design for the conductors 15 of the side circuits of a cable quad which are parallel to each other and, under ideal conditions, are free from coupling, involves an arrangement in which the transpositions take place in even pitch. A transposition arrangement in even pitch is shown in Figure 1 of the 20 drawing. The transposition sections on both side circuits are equal in length, a transposition on one side circuit taking place midway between two transpositions on the other side circuit. In practicing this transposition 25 scheme, it may occur through some necessary constructional measure or through a possible inaccuracy of slight order, that one of the movements of the transposing device employed in actual practice may be effected so 30 as to introduce a regularly recurring error. The transposing device may produce a transposition regularly at an angle slightly more or less than 180 degrees. Such an error may 35 be repeated continually under the same conditions, introducing a systematic coupling disturbance, which in a single section may not be appreciable, but which occurs constantly and, after passing through several sections, 40 introduces an additive effect of considerable proportions.

The two side circuits of a cable may be 45 provided with transposition sections of different lengths and still be in even pitch, i. e., the number of transposition schemes on one 50 side circuit for a given length may be some even multiple of the number of transposition sections on the other side circuit. In a transposition scheme in even pitch in which transpositions take place at different lengths in 55 the respective side circuits, a transposition on the side circuit having sparsely located transpositions may coincide with a transposition on the other side circuit having a greater number of transpositions at regular intervals. Such a transposition scheme is shown 60 in Figure 2 of the drawing. In this embodiment, each transposition section of the lower side circuit is four times as long as a transposition section in the upper side circuit. However, in such an arrangement, manufacturing irregularities, such as are described hereinabove, may also be presented. In addition to these manufacturing irregularities, 65 any irregular distribution of the transposi-

tions on the respective side circuits may be a further source of error introducing a disturbance in the balance between the side circuits. Thus, there is some disadvantage in having a pair of side circuits in which one of the side circuits has considerably fewer transposition sections than the other of the side circuits by virtue of the fact that small and ordinarily inappreciable coupling disturbances may occur at each transposition. 75

In the transposition scheme of this invention, it is intended to greatly minimize any coupling disturbances resulting from mechanical imperfections. This is accomplished by having the relative positions of the transpositions on the respective side circuits as diverse as possible in order that any possible schematic coupling errors, which may be inappreciable in a single transposition section, may not additively exceed some definite amount. At the same time it is intended to suitably transpose each side circuit at regular intervals, so that the number of transposition sections on one side circuit will not greatly preponderate over the number of transposition sections on the other side circuit. This may be accomplished by providing certain transposition schemes in uneven pitch in place of the schemes in even pitch. In order to more clearly understand the special transposition schemes in uneven pitch, which may bring about the above-mentioned advantages, even in view of practical manufacturing difficulties, it becomes necessary to examine somewhat closely different possible 100 forms of transposition schemes.

In quadded cabling in which the wires at two adjacent corners of a square cross-section represent one side circuit, the wires at the remaining two adjacent corners representing the other side circuit, the substantial elimination of crosstalk disturbances requires the use of a transposition scheme, in which the sum of the lengths of all transposition sections which are separated from the first section by an even number of transpositions, including the first section itself, be equal to the sum of the lengths of all sections separated from the first section by an uneven number of transpositions. Thus, the lengths of the transposition sections of both side circuits are to be added together, and the difference between the sum of all sections of the first (positive) kind and the sum of all sections of the second (negative) kind, will be called the effective disturbing length for that particular section of cable. 110

In the case of transpositions in even pitch, although transposition sections may be different from each other on the respective side circuits, these sections are individually equal to each other on the same side circuit. The lengths of the transposition sections on both side circuits may, however, be incommensurable. An incommensurable relationship be- 125 130

- tween the lengths of the transposition sections may, in practice, be closely simulated by some commensurable relationship. Accordingly, the length of a transposition section may be so chosen in a quad in which the side circuits run parallel to each other, that the transpositions at the ends of a definite length of cable coincide, while there is no coincidence of transpositions anywhere within that length. The length of the cable quad having equal sections on the respective side circuits providing coincident transpositions at its beginning and at its end, will be referred to hereinafter as the basic interval.
- 15 The basic interval may be considered as composed of m and n transposition sections on the respective side circuits, m and n being whole numbers. It will be assumed hereinafter that m is greater than n . Moreover, a basic interval may exist only when m and n represent relatively prime numbers. The lengths of the transposition sections are then conversely proportional to the number of transposition sections within the basic interval. Within the basic interval the length of a transposition section in a side circuit having m sections is proportional to n , and conversely, the length of a transposition section in the other side circuit is proportional to m .
- 30 In the case of transposition fields of different lengths arranged in even pitch, the following relationship will exist:

$$35 \quad \frac{1}{n} = \frac{m}{n} = 2^{ca} \quad (1)$$

in which c is a positive whole number and d is an odd number. n must necessarily be unity, for the right side of the Equation (1) would not have an integral value unless m were divisible by n and unless m and n were relatively prime numbers. This, obviously, can only be true when n is unity. Transpositions in uneven pitch are those in which the relationship between m and n , i. e. $\frac{m}{n}$ is not represented by an even integer. An arrangement in which the number of transposition sections in the basic interval is even in one side circuit and uneven in the other, the uneven number differing from unity, or vice versa, represents a case in uneven pitch. Also, an arrangement in which the transposition sections in the basic interval are uneven integers in the respective side circuits, even though the smaller number be unity, represents another case of uneven pitch. Of course, an arrangement in which the transpositions in both side circuits are even integers is not here considered because two even numbers are not relatively prime.

Suppose m to be even and n uneven and suppose that the initial transpositions on the two side circuits are coincident, then the trans-

sition $(1+km)$ of the side circuit with shorter spacings will coincide with the transposition $(1+km)$ of the side circuit with longer spacings, k being a positive whole number. Such an arrangement is illustrated in Figure 3 of the drawing in which m equals 8 and n equals 3. There a transposition on the side circuit of shorter spacing will lie between two transpositions on the side circuit of longer spacing, two short transpositions following each other consecutively. To calculate the effective disturbance, i. e., the effective disturbing length within a basic interval, it may be desirable to divide the basic interval into short and long transposition sections following each other alternately. Figure 3 shows portions of the arrangement enclosed by rectangles defined by dotted lines. The entire basic interval is symmetrical about a plane intersecting the quad at its center. Since only one transposition is located at the center of the basic interval, that transposition being in the side circuit of shorter spacing in which m is even, the two symmetrical transposition sections on both sides of the center line will be separated from each other by an uneven number of transpositions. Consequently, their disturbances will be mutually compensated, and the total effective disturbing length of the basic interval will be equal to zero. The same conclusions may be derived for the case in which m is uneven and n is even. Thus, in general, in the basic interval in which either m or n is even in one of the side circuits and uneven in the other of the side circuits, there is produced a balanced basic interval, and, consequently, a balanced cable quad, the relative positions of the transpositions on the respective side circuits being considerably more diverse than they are in the case of even pitch.

Figure 4 shows another arrangement in which m equals 3 and n equals 1. Since n equals 1, the conclusions derived hereinabove do not apply, and this particular case of uneven transpositions becomes of little interest.

Figure 5 shows an arrangement in which m and n are both uneven. Here m equals 11 and n equals 7. Moreover, the last transpositions on the respective side circuits are coincident. Where m and n are uneven, no transposition is located at the center of the basic interval. Two transposition sections which are symmetrical about the center are separated from each other by an even number of transpositions and, consequently, their disturbances are additive. In such an arrangement, each basic interval may be considered to have a transposition section exhibiting a positive charge at its beginning. The disturbances of the individual basic intervals are also additive. To eliminate interferences, it is essential that counteracting charges of equal magnitude be provided in each basic interval.

It is to be noted in the arrangement shown in Figure 5 that the transposition sections in the lower side circuit number 7 and alternate in respect to the character of the electrical charge. Since the number of transposition sections within the basic interval is uneven, the effective disturbance may be considered proportional to 7. It may be shown that in any arrangement in which m and n are both odd integers the effective disturbance is $+n$. It is also to be noted that at the left of the center, the lengths of the transposition sections in the space intervals of the first side circuit all appear as whole numbers, each greater than zero and less than 7. In other words, the numbers 1, 2, 3, 4, 5 and 6 occur, each occurring but once. Here, also, the even integers exhibit negative charges and the odd integers positive charges. It may readily be shown that this is generally true for any arrangement in which the number of transposition sections in the basic interval are odd in both side circuits. Thus, at the left of the center in the particular arrangement disclosed in Figure 5, the transposition sections include positive charges of $+1, +3, \dots, +\frac{(n-1)^2}{2}$, and negative charges of $-2, -4, \dots, -(n-1)$. The positive transposition sections in the space intervals within the basic interval on both the left and right-hand sides of the center contribute to the effective disturbance by

$$+\frac{(n-1)^2}{2},$$

and the negative transposition sections contribute to the effective disturbance by the amount

$$-\frac{(n^2-1)}{2}.$$

Thus, the entire disturbance, including both the positive and negative contributions, is

$$45 \quad n + \frac{(n-1)^2}{2} - \frac{(n^2-1)}{2} = +1. \quad (2)$$

Consequently, the effective disturbance within a basic interval in any arrangement in which both m and n are odd integers can never vanish. Thus, it becomes impossible to eliminate the effect of crosstalk disturbances by means of transpositions where m and n are both odd integers, when terminal transpositions within the basic interval in both said circuits are coincident, as assumed.

It is possible, however, to displace the basic interval on one side circuit with respect to the same interval on the other side circuit. It may be generally shown that in an arrangement in which m and n are both odd, the displacement of the terminal transposition of one side circuit with respect to the terminal transposition of the other side circuit to the extent of one-half the common measure of the transposition sections causes

the effective disturbance to become zero. A displacement of the basic interval in one side circuit to the same interval in the other side circuit by $1/2n$ may be made.

Figure 6 of the drawing shows the arrangement of Figure 5 where m equals 11 and n equals 7, the terminal transpositions being displaced by one-half with respect to each other. The arrangement in Figure 6 provides the following spacing within the basic interval upon the side circuit having fewer transpositions: 0; 0.5; 7; 11.5; 14; 21; 22.5; 28; 33.5=35; 42; 44.5; 49; 55.5; 56; 63; 66.5; 70; 77.

The spacing provided by the arrangement of Figure 6 produces the following disturbances: $+(7-0.5) + (14-11.5) + (22.5-21) + (33.5-28) + (42-35) + (49-44.5) + (56-55.5) + (66.5-63) + (77-70) = +6.5 + 2.5 + 1.5 + 5.5 + 7 + 4.5 + 0.5 + 3.5 + 7 = 38.5$.

Thus, the net positive disturbance is equal to one-half of the length of the entire basic interval. However, the negative transposition sections introduce a negative effective disturbance of -38.5 , the negative disturbance exactly compensating the positive disturbance.

The particular advantages to be derived from an arrangement having an odd number of transposition sections become even more evident as the number of transposition sections with the basic interval increases. Thus, it will be shown that there is considerable advantage in having m and n comparatively large numbers, these numbers representing one number of transposition sections within the basic interval in the respective side circuits, no periodicity or repetition of the relative positions taking place within that interval.

It is to be noted that a great increase in the magnitude of m and n does not necessarily imply a corresponding enlargement of the transposition sections. The length of the transposition section on one of the side circuits may be selected freely, the length of the sections on the other side circuits being determined from the relationship existing between m and n . If m or n be of substantially the same order of magnitude as their difference, then it may occur as a result of the practically insignificant variations in the length of the transposition sections, that m and n have a common divisor, whereupon the ratio of m to n becomes considerably smaller than anticipated. Thus, when m equals 1000 and n equals 499, the complete repetition of the relative positions of the transpositions on the two side circuits will, of course, occur only after 499 long transposition sections or after 1000 short transposition sections, respectively. Yet, if the longer transposition section be decreased in length by, for example, 1/500th of its design length, then the ratio of m to n may become

1000/500=2. Accordingly, the relative positions of the transposition sections will be repeated after two short sections or one of the longer sections, respectively, and the advantages mentioned hereinabove in connection with the employment of a great number of transposition sections within a basic interval disappears.

If, however, m and n be comparatively large numbers and their difference be small as compared to these numbers, then the difficulty outlined hereinabove may be avoided. If, for example, m equals 1000 and n equals 989, then, should n be increased by 1, the ratio of m to n would become $1000/990=100/99$. Here an increase in n by 1 causes a reduction in the number of transposition sections within the basic interval by almost 90%. The possibility of a decrease in the ratio of m to n because of the occurrence of a common divisor is further limited by the fact that even after proper allowance has been made for the elimination of the common divisor, the ratio of m to n must necessarily be a whole number which is at least unity. In the case in which both m and n are comparatively large numbers, it may be assumed that

$$30 \quad \frac{m-n}{m} = e \text{ or } m = \frac{m-n}{e}.$$

Then, if the transposition sections be improperly accomplished in practice, resulting in a reduction in the values of m and n , the reduced magnitude of m such as m'

$$35 \quad \geq 1/e.$$

By reducing the value of e , the order of magnitude of m and also that of n , initially of the same order of magnitude, may be safely kept at a suitably high value. Consequently, the number of transpositions on the side circuits should not differ from each other too much, so that any unequal distribution of the transpositions on the respective side circuits will not result in disturbing capacitative unbalances. In general, a difference in the number of transpositions on the respective side circuits in excess of 20% may become objectionable. This permissible percentage limitation depends on the accuracy to be accomplished in practice in the formation of the transpositions as well as on the degree of immunity from interference required.

If m and n be comparatively large numbers whose difference is small as compared to these numbers, as mentioned hereinabove, then the various cases of transpositions in uneven pitch, i. e., those in which m is even and n uneven, or vice versa; those in which m and n are both uneven, having terminal transpositions which are coincident within the basic interval and which have imperfect interference elimination in practice; and those in which m and n are both uneven, hav-

ing terminal transpositions which are relatively displaced, are practically not distinguishable. Where m , for example, equals 1000 and n is 989, the first transpositions within the basic interval being coincident, a general 70 limiting case of an irregular transposition scheme is provided in practice, corresponding to an arrangement in which m equals 100 and n equals 99. Interference may be eliminated within a basic interval including 100 75 short transposition sections or 99 long transposition sections, respectively, as mentioned hereinabove.

Taking into consideration the unavoidable irregularities of the sections in practice, 80 if a case be assumed in which m equals 999 and n equals 989, these numbers being relatively prime with respect to each other, and the terminal transpositions within the basic interval being coincident, there will be a disturbance within the basic interval which will not vanish. As may be assumed in all cases in which both m and n are uneven, the disturbance may amount to ± 1 . In other words, the disturbing length within the basic interval will amount to substantially 90.

$$\frac{1}{1,000,000}^{\text{th}}$$

of the length of the basic interval. In the 95 case assumed, the denominator becomes the product of 989 and 999 or 980,011. This arrangement, having uneven values for m and n and coincident terminal transpositions, is practically free from interference. However, 100 by displacing the terminal transpositions by $1/2$ with respect to each other, the disturbance may be completely eliminated. Accordingly, in the three types of transpositions in uneven pitch specifically enumerated hereinabove, in all of which there are the same relative positions of the transpositions on the respective side circuits within the basic interval, the basic interval containing essentially 99 long sections and 100 short sections 105 and coincident terminal transpositions, the disturbance or effective disturbing length 110 may be completely eliminated.

The following table shows the characteristic values for the three types of transposition schemes mentioned hereinabove:

m:n	I	II	III	120
	100:99	1,000:989	999:989	
Greatest common measure	1 mm.	0.1 mm.	0.1 mm.	
Transposition section on circuit having greater number of transpositions	99 mm.	98.9 mm.	98.9 mm.	
Transposition section on circuit having smaller number of transpositions	100 mm.	100 mm.	99.9 mm.	125
Length of basic interval in common measure	9900	989000	988011	
Length of basic interval in absolute measure	9900 mm.	989000 mm.	98801.1 mm.	

It may frequently be desirable to have the 130

cable as free from interference as possible, regardless of the place where it is intersected. Of course, a cable having individually balanced basic intervals and consisting of a 5 whole number of these intervals, will have a negligible disturbing length regardless of the point in the basic interval considered as its beginning or as its end. But this is not true in the case of the cable which does not 10 consist of an integral multiple of individually balanced basic intervals. The disturbing length in the latter case may, however, be substantially suppressed, if desired, by allotting to the greatest common measure of 15 the transposition sections on the two side circuits whose absolute magnitude is arbitrary, a very small value. Thus, it appears desirable to maintain the transposition sections on the side circuits comparatively small.

20 To increase the possible number of mutual positions of the conductors of the quad, the method of accomplishing the transposition scheme may be changed to thereby increase its effectiveness. Accordingly, a single side circuit may be transposed, first in one direction and then in the other. Thus, the first transposition may be accomplished by turning one conductor about the other to the right through an angle of 180 degrees, followed by a turn in 25 the reverse direction through 180 degrees; then, by a transposition to the left through 180 degrees; then by a turn in the reverse direction, and so on. Accordingly, one of the conductors of one side circuit and then the 30 other of its conductors are alternately located adjacent to the second circuit. Such an arrangement may be brought to an even higher efficiency by preventing the coincidence of transposition sections exhibiting the same 35 relative positions in both side circuits.

40 While this invention has been shown and described in one particular embodiment merely for the purpose of illustration, it will be understood that the general principles of this 45 invention may be embodied in other and widely varied organizations without departing from the spirit of the invention and the scope of the appended claims.

What we claim as new and desire to secure 50 by Letters Patent of the United States, is,—

1. The method of constructing a cable quad which consists in twisting the four wires of the quad about a common axis, transposing one pair of wires so as to form m sections per 55 unit of length, and transposing the other pair of wires so as to form n sections in the same unit of length, m and n representing relatively different, prime odd integers.

2. The method of constructing a cable quad 60 which consists in transposing one pair of wires of a quad representing one side circuit so as to form an odd number of sections within a predetermined interval, and transposing the other pair of wires of the quad representing 65 the other side circuit so as to form a dif-

ferent odd number of sections within the predetermined length, the number of sections in the respective side circuits being relatively prime numbers.

3. The method of constructing a cable quad 70 which consists in transposing one pair of wires representing one side circuit so as to form a definite number of sections within a predetermined interval, transposing the other pair of wires of the quad representing the 75 other side circuit so as to form a different number of sections within the same predetermined interval, the number of sections in one side circuit bearing a ratio to the number of sections in the other side circuit as do two odd 80 prime integers, and displacing one pair of wires with respect to the other pair of wires by a predetermined distance.

4. A cable quad to be employed for the 85 transmission and reception of telephone messages, comprising four wires wound about a common axis having point-like transpositions equally spaced in each pair of wires, the length of the transposition sections in one pair of wires bearing the relation to the lengths of 90 the transposition sections in the other pair of wires in accordance with two prime unequal integers, one of which is an odd integer different from unity, one pair of wires being displaced with respect to the other pair of 95 wires by a predetermined distance.

In witness whereof, we have hereunto set our hands this 25th day of October, 1927.
